UNITED STATES PATENT OFFICE.

WILLIAM F. GAMMETER, OF CADIZ, OHIO.

TIRE-MACHINE DRUM.

1,332,330.

Specification of Letters Patent.

Patented Mar. 2, 1920.

Application filed August 16, 1919. Serial No. 317,914.

To all whom it may concern:

Be it known that I, WILLIAM F. GAMMETER, a citizen of the United States, residing at Cadiz, in the county of Harrison and 5 State of Ohio, have invented certain new and useful Improvements in Tire-Machine Drums, of which the following is a specification.

This invention relates to improvements in 10 stock shells or drums and is designed more particularly as an improvement on the shell or drum shown in my Patent No. 1,104,296, issued July 21, 1914.

In the patented structure there is provided in each end of the body of the drum, a head having a polygonal opening to receive the polygonal shaft or spindle upon which the drum is supported and by which it is rotated, a tubular core being fitted at its 20 ends to the said head and extending axially within the drum to receive the said shaft or spindle and strengthen and reinforce the engagement between the parts. The present invention is directed chiefly to a novel 25 means for securing together the said heads in the ends of the drum and the ends of the said tubular core whereby these parts will be rigidly united and securely braced with relation to each other, the means provided for this purpose serving also in an 30 effectual manner to prevent the heads being driven into the drum beyond their proper positions and to prevent the heads being pried or forced out from the ends of 35 the drum.

Another object of the invention is to provide a connection between the heads and the ends of the core which may be conveniently secured at a low cost of production 40 and which will serve in the most positive manner to secure together these parts.

In the accompanying drawings:

Figure 1 is a perspective view, parts being broken away, illustrating a partially completed drum constructed in accordance with the present invention;

Fig. 2 is a vertical longitudinal sectional view therethrough;

Fig. 3 is an end elevation of the drum;

Fig. 4 is a perspective view of one end of the core before its connection with its respective head;

Fig. 5 is a transverse sectional view illustrating a modified form of core.

55 In the drawings the numeral 1 indicates in general the body of the drum which body

is formed from sheet metal of the required gage and rolled to cylindrical form, the body being provided as is customary, in the manufacture of drums of my invention, with 60 a longitudinally extending groove or channel 2 to receive the end edge of the sheet 3 of rubber or other material to be wound upon the drum.

As in the patented structure, a head is 65 arranged in each end of the drum and each of these heads, indicated in general by the numeral 4, comprises a substantially circular sheet metal body 5 having a peripheral flange 6 projecting from its outer face, the flanged 70 periphery of the head being frictionally or otherwise secured within the respective end of the body of the drum. This head may be positioned directly at the end of the drum or it may be spaced inwardly from the end 75 of the drum any desired distance. In order to receive the ends of the tubular core, the bodies of the heads 5 are formed centrally with polygonal openings 7.

In that form of the invention shown in 80 Figs. 1 to 4 inclusive, the core is formed in two sections and in the form shown in Fig. 5, it is formed in four sections. Also in each illustrated form the core is rectangular in cross section to receive a correspondingly formed mandrel or shaft (not shown) although it will be understood that the shaft and core may have some other polygonal cross section if found desirable and consequently the core may be formed in more 85 than four sections without departing from the invention. In the drawings the core is indicated in general by the numeral 8 and in the two-part form comprises counterpart sections each having right angularly extending wings 9 which form two walls of the core, each wing being provided at its free longitudinal edge with an outstanding flange 95

10. When the sections are assembled, these flanges are disposed in contact and registration as shown in Figs. 1 and 4 of the drawings and are secured together by means of rivets or other suitable securing elements 100 11. The flanges 10 terminate short of the ends of the core so as to provide oppositely 105 located shoulders 12 spaced inwardly from each end of the core. In a line with the bend forming the juncture between the wings 9 comprising each section of the two-part core shown in Figs. 1 to 4 inclusive, each 110 section is formed with a slit or incision 13 preferably extending inwardly from the end

of the core the same distance that the shoulders 12 at the ends of the flanges 10 are spaced inwardly from the corresponding ends of the core. Thus at each end of each 5 wall or side of the core there is formed a tongue indicated by the numeral 14. In assembling the core with the heads 4, each end of the core is inserted into the opening 7 in the respective head so that the shoulders 12 10 will abut squarely against the inner face of the respective head. The tongues 14 are then struck down so as to bear firmly against the outer or opposite face of the said head 4, and rivets or other suitable securing elements indicated by the numeral 15 are secured through the said tongues and the body 15 of the head, and these parts are in this manner permanently and securely united. As a result of this construction there are 20 no rivet heads or other obstructions offered to the insertion of the shaft or mandrel into the core, the inner surfaces of the walls or sides of the core being left intact and unobstructed. It will be evident at this point 25 that the engagement of the bodies or webs of the heads against the shoulders 12 serve effectually to prevent the heads being driven into the drum beyond their properly located positions, and on the other hand the 30 tongues 14 serve effectually to prevent the heads being driven out through the ends of the drum.

In that form of the invention shown in Fig. 5 in which the core is formed from 35 four sections, each section indicated by the numeral 16, constitutes one side or wall of the core and each is formed at each of its longitudinal edges with an outstanding flange 17, these flanges corresponding to the flanges 10 and being secured together in 40 the manner heretofore described. In this form of the invention all of the flanges will, of course, terminate short of the ends of the core so that the web or body of each 45 section will project at its ends beyond its flanges to provide tongues corresponding to the tongues 14.

Any suitable form of spider or bracing head 18 and any number of these heads desired, may be positioned upon the core and within the body of the drum so as to not 50 only prevent the breaking down of the intermediate portion of the drum but also to prevent distortion or bending of the core.

55 Having thus described the invention, what is claimed as new is:

1. In a device of the class described, a tubular mandrel receiving core flanged longitudinally and receiving drum heads 60 spaced apart with respect to each other by said longitudinal flanges, and means integral with said core and projecting through and engaging with said drum heads to permanently associate the same with said core.
- 65 2. In a device of the class described, a

tubular mandrel receiving core formed of longitudinally flanged connected abutting members and receiving drum heads spaced apart with respect to each other by said longitudinal flanges, and means integral with 70 said core and projecting through and engaging with said drum heads to permanently associate the same with said core.

3. In a device of the class described, a tubular mandrel - receiving core having a 75 longitudinal seam and provided at its seam with outstanding flanges terminating short of one end of the core, and a drum head fitted onto the core and engaging at one side against the said ends of the flanges, the core 80 beyond the ends of the flanges being flanged against the other side of the said head.

4. In a device of the class described, a tubular mandrel - receiving core having a longitudinal seam and provided at its seam 85 with outstanding flanges terminating short of one end of the core, a drum head fitted onto the core and engaging at one side against the said ends of the flanges, the core beyond the ends of the flanges being flanged 90 against the other side of the said head, and securing elements secured through the said flange and the said head.

5. In a device of the class described, a tubular mandrel-receiving core comprising 95 sections provided with meeting flanges whereby they may be united, the flanges terminating short of one end of the mandrel, and a drum head fitted onto the said end of the core and bearing at one side 100 against the ends of the said flanges, the said ends of the sections being formed with flanges engaging against the other side of the said head and holding the head in engagement with the said ends of the first 105 mentioned flanges.

6. In a device of the class described, a tubular mandrel-receiving core of polygonal cross section comprising assembled sections having longitudinal extending meeting 110 flanges whereby they may be united, the flanges terminating short of one end of the core, a drum head fitted onto the said end of the core and engaging against the said ends of the flanges, the said end of the core being turned back to provide flanges bearing 115 against the outer face of the said head, and means securing the last mentioned flanges to the head.

7. In a device of the class described, a 120 tubular mandrel-receiving core polygonal in cross section and comprising assembled sections, each section including relatively angularly disposed wings and each being provided at its free longitudinal edges with 125 flanges, the flanges of the sections being disposed in meeting relation and terminating short of one end of the core to provide shoulders spaced inwardly from the said end of the core, the sections being each provided 130

- with an incision in a line with the juncture between its wings and extending inwardly from the said end thereof, and a drum head fitted onto the said end of the core and engaging at one side against the shoulder formed by the ends of the flanges, the ends of the wings of the sections being bent back to provide flanges engaging against the other face of the head.
- 10 8. As a new article of manufacture, a mandrel-receiving core for a drum of the

class described of tubular form and polygonal cross section, the said core being provided with flanges in a line with the juncture of adjacent ones of its sides, and other sides of the core being divided in a line with their juncture at one end of the core, the said flanges terminating short of the said end of the core.

In testimony whereof I affix my signature. 20

WILLIAM F. GAMMETER. [L.S.]
